UNITED STATES PATENT OFFICE

PAUL E. LEHMAN, OF WOODMERE, NEW YORK

DESIGN FOR A BOTTLE HOLDER OR SIMILAR ARTICLE

Application filed August 11, 1932. Serial No. 44,581. Term of patent 7 years

To all whom it may concern:

Be it known that I, PAUL E. LEHMAN, a citizen of the United States, residing at Woodmere, county of Nassau, and State of New York, have invented a new, original, and ornamental Design for a Bottle Holder or Similar Article, of which the following is a specification, reference being had to the accompanying drawing, forming a part thereof.

The figure is a perspective of a bottle holder showing my new design.

I claim:

The ornamental design for a bottle holder or similar article substantially as shown.

PAUL E. LEHMAN,
